FUSE

William Summerbell, Washington, D. C.; Edith May Summerbell executrix of said William Summerbell, deceased

Application August 22, 1946, Serial No. 692,154

2 Claims. (Cl. 102—75)

(Granted under the act of March 3, 1883, as amended April 30, 1928; 370 O. G. 757)

1

The invention described herein may be manufactured and used by or for the Government for governmental purposes, without the payment to me of any royalty thereon.

My invention relates to fuzes, particularly to an impact type fuze of a character adapted to be retained in the base plug of a projectile which is fixed in a cartridge case and fired from a rifled barrel whereby it is rotated in flight.

Heretofore considerable difficulty has been encountered in providing fuzes of a character which were capable of being arranged for mechanical delay in exploding the primer charge of the projectile, and at the same time be able to withstand rough handling of the shell without risk to premature arming, unless externally controlled safety devices requiring adjustment before firing were installed. The use or necessity for such safety devices has been eliminated in my invention.

The primary object of my invention is to provide an impact fuze of the character described which has mechanical means for delaying the exploding of the primer charge, and in which all externally controlled safety devices requiring adjustment before firing are eliminated.

A further object of my invention is to provide a fuze in which the danger of accidental arming either from rough handling of the projectile before firing, or from set back forces set up within the fuze itself after firing, is eliminated.

A still further object of my invention is to provide a fuze which is both simple in construction, and efficient in operation.

Other objects and advantages of the invention reside in the construction and arrangement of parts involved in the embodiment of the invention, as will be understood from the following description and accompanying drawings, forming part of the specification, wherein similar numbers are used to indicate the same part throughout the specification and drawings. In these drawings.

Figure 1 is a broken fragmentary section view of an artillery projectile, showing the invention in place.

Figures 2, 3 and 4 are cross-sections of a fuze embodying the invention and illustrate the operation of the fuze.

Figure 5 is a broken fragmentary section of a modification of the invention with delaying element omitted.

Figure 6 is a transverse section of the fuze, taken on line 6—6 of Figure 2, with the trigger shown in the unarmed position, and

2

Figure 7 is a fragmentary sectional view of a modified form of the delaying element.

Referring now in detail to the accompanying drawings, and in particular to Figures 1 through 4, the numeral 8 indicates generally an artillery projectile fixed in a cartridge case 9 and having a steel body 10, a bursting charge 11 contained within a cavity provided in the said body, a rotating band 12 whereby the projectile is rotated in flight, and a base plug 13. The plug 13 is externally threaded as at 14 for attachment to the steel body 10, and a bored cavity 15 of multiple diameter, internally threaded as at 16, is provided for a purpose which will be herein-after explained. The base plug 13 is also provided with a smaller rear cavity 17 to receive a tracer pellet 18.

The numeral 19 designates generally the fuze of applicant's invention which is shown in Figure 1 positioned within the cavity 15 provided for this purpose in base plug 13. It has a hollow steel body or housing comprising a rear or cup section 20 having a rear portion of smaller diameter than its forward portion and adapted to fit snugly in the smaller diameter inner portion of the cavity 15 in the base plug 13, and a front or cap section 21.

A firing pin 22 is held firmly within the smaller diameter portion of cup section 20 by pressure of the side walls of said section. It is positioned adjacent the bottom of the cavity 15, its forward movement being arrested by an annular shoulder 23 formed in the said side walls.

The front or cap section 21 is formed with a partition 24 intermediate its ends to divide the said cap 21 into two separate cavities. A forward cavity 25 houses a detonator charge 26 which is retained within the said cavity by a threaded screw plug 27 provided with a vent or opening 28 communicating with the bursting charge 11. The diameter of the larger rear cavity 29 is the same as the inner diameter of the larger forward portion of cup section 20. Screw threads 30 are provided about the outer periphery of cap section 21 to engage the threads 16 formed in the base plug 13, and a flame vent 31 is provided in partition 24 for passage of flame between the said cavities 25 and 29.

A cylindrical collar 32, preferably made of brass, is positioned within the passage formed by the cavity 29 and the forward inner portion of cup 20, the said collar being of a slightly smaller outer diameter than the inner diameter of said passage so that it may move easily forward through said passage upon impact of the projectile 8 against the target. Rearward move-

ment of said collar upon setback is prevented by the annular shoulder on cup 20. The collar 32 is provided with a hole 33 into which is forced a metal pin 34 strong enough to withstand rough handling of the projectile before loading in the gun but which will collapse or shear upon impact of the projectile against a target. The pin 34 engages within a recess 35 formed in a curved or wishbone trigger 36 to hold the said trigger 36 in an unarmed position so long as the said trigger 36 remains in engagement with a cylindrical primer charge holder 37 in a circumferential groove 38 formed in the surface of the holder 37 and shaped to fit the contour of the trigger 36.

Primer charge holder 37 is arranged with axial bores 39 and 40 at opposite ends thereof, the said bores 39 and 40 being connected by a centrally disposed smaller diameter bore 41. The bore 39, at the end of the holder 37 facing the firing pin 22, is closed by a threaded screw plug 42, forming a cavity within the said bore which houses a conventional primer charge 43. A centrally disposed small bore 44 provides a passage therethrough for the firing pin 22 in making contact with primer charge 43. Bore 40, at the other end of holder 37, is left open permitting it to slide over a cylindrical delay sleeve 45, the said delay sleeve 45 being slightly tapered so that it will fit within the said bore 40 and be held therein by friction. A compressible coil spring 46 is disposed within the axial bore 47 of the sleeve 45 and held in slight compression between the bottom of bore 40 and the partition 24. The function of the said spring 46 will be later explained.

The operation of the fuze is as follows: While the projectile is in flight after firing, the fuze remains in an unarmed condition since pin 34 is not affected by setback forces. However, the force of inertia upon impact overcomes the resistance of pin 34 and it is sheared. Collar 32, freed from the restraint of the said pin 34, continues forward within the fuze, releasing the trigger 36 from its engagement within groove 38 in holder 37. Holder 37 moves forward upon the tapered end of delay sleeve 45 against the restraint of the spring 46 and is held frictionally thereon. These members remain locked in such delaying position and prevent contact between the primer charge 43 and firing pin 22 during deceleration of the projectile. When deceleration ceases, the primer charge holder 37 containing the primer charge 43, with the delay sleeve 45 frictionally attached thereto, is forced rearwardly by the releasing energy of the spring 46 until the firing pin 22 strikes and ignites the said primer charge after passing through the bore 44 in screw plug 42. The rearward movement of the holder 37 is slow and sluggish because of the added weight of the frictionally attached delay sleeve, thus increasing the delaying action of the fuze. The flame from the ignited primer 43 passes through bores 41 and 40, explodes the detonator 26 in cavity 25, and the explosive force of the said detonator is transmitted through the opening 28 to the bursting charge in the body of the projectile.

In Figure 7, the numeral 48 shows another form of delay sleeve wherein a shoulder 49, with set-back, has been substituted in lieu of the taper of delay sleeve 45 already described. In operation, delay sleeve 48 functions in the same manner as delay sleeve 45 heretofore described.

In the embodiment of the invention shown in Figure 5 the delay sleeve has been entirely omitted. The effect of omitting the sleeve is the

elimination of the added delaying action, and the fuze of this embodiment will function with less delay upon impact against a target. In all other respects the operation of the fuze will be as heretofore described.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described the invention, I claim:

1. A base detonating fuze having a movable cylindrical holder for its primer charge, said holder being circumferentially grooved intermediate its ends and held in an unarmed position by a wishbone shaped trigger in said groove, a restraining collar embracing said trigger with a sliding fit and held thereon by shearable means to release the trigger upon impact; a delaying sleeve longitudinally aligned with said holder, said sleeve having a tapered end normally partially inserted in said holder, said holder and sleeve telescoping upon impact and remaining immovable during deceleration; a compressible coil spring, housed within a bore of the delay sleeve to force the sleeve and primer charge holder rearward against a firing pin fixed in the body of the fuze.

2. A base detonating fuze comprising a cylindrical body having reduced elongated ends forming transverse vertical walls and a chamber therebetween, one of said ends having a firing pin fixed therein, the other of said ends housing a detonator, a bored primer charge holder circumferentially grooved intermediate its ends positioned in said chamber, said holder having a primer charge end in slidable engagement with the one of said ends, the opposite end of said holder being internally tapered and in slidable engagement with the externally tapered surface of a bored delay sleeve releasably seated in the wall of said other end, a spring within the bore of said holder and said delay sleeve resiliently spacing said holder and said delay sleeve, a U-shaped trigger in said circumferential groove, said trigger embraced by a collar in shearable relationship, said collar moving forward and disengaging said trigger upon impact, said trigger moving radially out of said groove, said holder moving forward to frictionally engage the tapered surface of said delay sleeve and to compress said spring, said spring returning said holder and sleeve after deceleration to impinge said primer charge upon said firing pin.

WILLIAM SUMMERBELL.
